UNITED STATES PATENT OFFICE.

FRITZ KRESS, OF DRESDEN, GERMANY.

GASIFIER FOR LIQUID FUEL.

Application filed March 15, 1926, Serial No. 94,678, and in Germany March 16, 1926.

The present invention has for its object a gasifier for liquid combustible and suitable for soldering lamps, boiling apparatus or the like. In said gasifier the tube supplying combustible is continued to or approximately to the forward extremity of the burner-tube; furthermore it is situated within the sphere of the flames issuing from the burner and connected with the gasifying conduit 5 situated within the burner-tube. The novelty of the gasifier consists in that the supply-tube is arranged with projections, ears or the like situated within the sphere of the burner-tube in such a manner that a heating of said projections or ears is caused by the flames issuing from the burner-tube and a better heating-effect on the supply-tube and thereby a better gasification is obtained.

20 The object of the present invention is represented in the drawing annexed in an example of construction. Fig. 1 is a side elevation of the gasifier and Fig. 2 a section according to line A B.

25 As clearly seen from the drawing, *a* is the burner-tube arranged in a well known manner with apertures *b*; *c* is the pipe supplying the combustible, continued up to the forward extremity of the burner-tube and forming a continuation of the gasifying tube *d* arranged within the burner-tube. On each side of the pipe *c* for supplying the combustible a projection or ear *e* is arranged which is touched by the radially issuing 30 flames and heated in such a manner that a better heating-effect on the supply-tube and thereby a better gasification of the combustible passing through said supply-tube is ensured. The projections or ears *e* provided 35 on the supply-tube are arranged in such a manner that the flames otherwise issuing through the aperture without any utiliza-

tion are used also for a better gasification within the supply-tube and for a better heating of the burner-tube and of the gasifying conduit situated within the burner-tube. The projections or ears or the like can be arranged with perforations for allowing a passage to the burning flames striking against the projections or ears and causing 50 a more intense heating of said projections or ears.

What I claim is:

1. In a gasifier for a liquid combustible, a burner tube having a series of radially placed apertures at the forward end thereof, a supply tube associated with the burner tube for supplying a combustible thereto, the said supply tube extending to approximately the forward end of the burner tube, 55 and apertured projections on the said supply tube, the said projections and the apertures therein being so placed that flames issuing from the radially disposed apertures in the burner tube impinge upon the said projections and enter the apertures therein to heat the projections and the said supply tube.

2. In a gasifier for a liquid combustible, a burner tube having a series of radially placed apertures at the forward end thereof, a supply tube associated with the burner tube for supplying a combustible thereto, the said supply tube extending to approximately the forward end of the burner tube, and a plurality of projections so placed on the supply tube that flames issuing from the radially disposed apertures in the burner tube impinge upon the said projections at substantially right angles thereto.

In testimony, that I claim the foregoing as my invention, I have signed my name this 26th day of February, 1926.

FRITZ KRESS.
